UNITED STATES PATENT OFFICE.

ALLIE H. HICKS, OF OMAHA, NEBRASKA.

HAIR CLIPPER.

Application filed August 28, 1925. Serial No. 53,159.

This invention relates to improvements in motor operated hair clippers.

In the use of the ordinary clipper, the hair, as it is cut from the head, is permitted to fall to the floor or onto the apron which is worn by the person whose hair is being cut. This creates an insanitary condition and likewise causes annoyance to the patron of the barber shop inasmuch as the shorter or fine hairs 10 are liable to fall upon his neck and cause discomfort. Likewise, this ordinary method of procedure renders necessary the frequent sweeping of the floor of the shop so that the hairs are thrown into the air together with 15 dust and dirt from the floor. In consideration of the foregoing the present invention has as its primary object to provide, in connection with motor operated hair clippers, means for automatically collecting and disposing of the hairs as they are clipped from the head so that they will not fall upon the 20 patron and cause annoyance, nor will they fall upon the floor and necessitate subsequent cleaning of the floor.

More specifically, the present invention has as its object to provide means for creating suction with a tube which has an intake located in proximity to the blades of the clippers, so as to collect and draw through 30 the tube the hairs clipped from the head, and further to provide means for directing these hairs into a suitable closed receptacle.

Another object of the invention is to so construct the means for disposing of the 35 clipped hairs, that it will not in any way interfere with use of the clippers in the ordinary manner and will, in fact, facilitate manipulation of the clippers as the blades thereof will be automatically cleared of hair 40 which would otherwise accumulate thereon and tend to obscure the blades from view.

In the accompanying drawings:

Figure 1 is a perspective view of the device embodying the invention arranged for 45 use.

Figure 2 is a view partly in elevation and partly in vertical section illustrating a portion of the device.

Figure 3 is a bottom plan view of the rotor 50 of the suction creating unit of the device.

Figure 4 is a vertical longitudinal sectional view of the intake nozzle of the device, the clippers upon which the nozzle is mounted being shown in elevation.

Figure 5 is a fragmentary plan view of the 55 nozzle detached from the clippers.

Motor operated hair clippers of the general type in connection with which the device of the invention will be embodied comprise a motor of the electric type which is 60 indicated in the drawings, in general, by the numeral 1, clipper mechanism which is indicated in general by the numeral 2, and which comprises the usual substantially flat and narrow oblong casing 3 housing the 65 operating mechanism for the clippers (not shown), and the clippers proper, the blade members of which are indicated by the numeral 4, a flexible shaft 5 being connected at one end to the operating mechanism which is 70 contained within the casing 3 and, at its other end, being connected, ordinarily, to the shaft of the electric motor 1, which shaft is indicated by the numeral 6. As previously 75 explained, however, in the use of motor driven clippers thus constructed, the clipped hair is permitted to fall upon the apron worn by the patron of the barber shop or onto the floor, and the disadvantages of this feature 80 have been fully pointed out above.

In accordance with the principles of the invention, the hair as it is severed by the clipper blades 4, is drawn by suction into an intake nozzle, thence through a tubular conduit, through the suction created by a suction creating device, and delivered into a bag where it is collected and from which it may be discharged from time to time as occasion 85 may require. The suction creating device comprises a casing 7 which includes a fixed 90 section 8 having a tubular concentric neck 9 extending from the outer side thereof and connected in any suitable manner to the casing of the electric motor 1, and this neck is provided with a bore 10 to rotatably receive 95 the projecting end of the motor shaft 6 and likewise receive one end of a shaft 11 upon which there is fixed the rotor of the suction creating device, as indicated in general by the numeral 12. The casing is provided with 100 a removable section 13 closing its opposite side and removably secured in place by screws 14. The rotor 11 comprises a hub 15 having an integral circular head 16 which is rotatably received substantially flush within a shallow recess 17 formed in the wall of the casing. Blades 18 radiate from the hub 15 105 and are preferably of the curvilinear con-

tour illustrated in Figure 3 of the drawings. Within the removable section 13 of the casing there are formed a number of openings 19 through which the air currents, induced 5 by the rotation of the rotor, pass, as indicated by the arrows, in Figure 2 of the drawings. The casing 7 is provided with a tangentially disposed discharge nozzle 20 to which is removably fitted the neck 21 of a 10 bag 22 which may be of cloth or any other suitable flexible and comparatively porous material and into which the clipped hair is to be delivered, in the operation of the device.

The numeral 23 indicates a hollow, substantially funnel-shaped coupling which is provided at its larger end with a circumscribing flange 24 through which securing screws 25 are fitted for the purpose of removably securing the coupling to the casing section 13, and to the smaller end of the coupling, or, in other words, its outer end, there is connected one end of a tubular flexible conduit 26 through which air is to be inducted to convey the clipped hairs to the 20 casing of the suction creating device. The shaft 11 of the rotor 12 projects into the coupling 23 and has connected to it the other end of the flexible shaft 5, the flexible shaft extending longitudinally within the tubular 25 conduit 26. The other end of the tubular conduit 26 is fitted, as at 27, to the inner end of the intake nozzle heretofore referred to and indicated in general by the numeral 28. This nozzle comprises a substantially 30 flat shank portion which is disposed upon the upper side of the casing 3 of the clipper mechanism and has its outer end portion turned downwardly as indicated by the numeral 29 so that its intake end will be positioned substantially above the forward ends 35 of the blades 4 of the clippers 2. This end of the intake nozzle is considerably widened, as indicated by the numeral 30, so that its mouth will extend entirely across the upper sides of the series of blades 4, and the 40 upper wall of the mouth is upwardly and outwardly flared as indicated by the numeral 31, so that the mouth is of greater height at its intake end than at its juncture with the 45 downturned portion 29 of the shank of the nozzle, and is consequently well adapted to receive all of the hairs severed by the blades of the clippers. The nozzle is preferably 50 provided in rear of the laterally disposed widened portion of the nozzle mouth 30, with an attaching ear 32 for the engagement therethrough of the shank of the tensioning screw 33 of the clippers 2, although the nozzle might be secured in any other suitable 55 manner to the clippers. The rear end of the shank of the nozzle, where it is connected with the intake end of the tubular conduit 26, is turned downwardly to engage behind the rear end of the casing 3 and is provided

with an opening 34 to accommodate the 65 usual neck extension 35 through which the flexible shaft 5 extends.

In order that the flexible shaft 5 may rotate freely and be packed in grease and, likewise, in order to prevent the clipped 70 hair which is drawn through the tubular conduit 26, coming in contact with said shaft, a tubular flexible sheath 36 is disposed to surround the said shaft 5 throughout its length and grease or other lubricant 75 may be introduced into this sheath.

It will be understood from the foregoing description of the invention that as the hairs are clipped through the reciprocation of the movable blades of the clippers 2, they will 80 be drawn by suction into the intake nozzle 28 and through the conduit 26 and coupling 23, and delivered through the nozzle 20 into the receptacle 22, so that none of the hairs will fall upon the apron which is draped 85 over the patron of the barber shop in which the device is used, nor will any of the hairs fall to the floor.

Having thus described the invention, what I claim is:

1. In combination with an electric motor, clipper mechanism and a flexible shaft between the said motor and clipper mechanism, of a shaft forming coupling means between the shaft of the motor and the said flexible shaft, a casing secured to the casing of the motor and having the coupling shaft mounted therein and provided with an inlet and an outlet, a funnel shaped coupling attached to the inlet side of the casing, a suction creating member within the casing and secured to the said coupling shaft, a nozzle adjacent the clipper mechanism and a conduit receiving and housing the flexible shaft and forming connecting means between the said nozzle and the funnel shaped coupling.

2. In combination with an electric motor, clipper mechanism and a flexible shaft between the said motor and clipper mechanism, of a coupling shaft connecting the flexible and motor shafts, a casing having a neck portion secured to the casing of the motor and receiving the adjacent ends of the said coupling and motor shafts, and having an outlet and an open side, a closure for the open side of the casing having inlet openings and receiving an end portion of the coupling shaft which is mounted therein, a suction creating member within the casing secured to the coupling shaft, a nozzle associated with the clipper mechanism to receive the clippings, a funnel shaped coupling attached to the closure at the open side of the casing and a conduit receiving the flexible shaft and connecting the nozzle and the funnel shaped coupling.

In testimony whereof I affix my signature.
ALLIE H. HICKS. [L. s.]
